UNITED STATES PATENT OFFICE

165,814

RADIO CABINET

Samuel E. Adler, Chicago, Ill., assignor to Admiral Corporation, Chicago, Ill., a corporation of Delaware

Application February 13, 1951, Serial No. 14,208

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Radio Cabinet, of which the following is a specification, reference being had to the accompanying drawings, forming part thereof.

Fig. 1 is a front elevational view of a radio cabinet showing my new design;

Fig. 2 is a fragmentary sectional view on line 2—2 of Fig. 1;

Fig. 3 is an elevational view of the right side of the cabinet;

Fig. 4 is a fragmentary sectional view on line 4—4 of Fig. 1; and

Fig. 5 is a fragmentary sectional view on line 5—5 of Fig. 1.

The left side of the cabinet resembles the right side and the back is plain.

I claim:

The ornamental design for a radio cabinet, as shown and described.

SAMUEL E. ADLER.
